TUBE CUTTER

Glenn W. Wolcott, Dayton, Ohio, assignor to Penn Aircraft Products, Incorporated, Dayton, Ohio, a corporation of Ohio

Application December 30, 1947, Serial No. 143,448

Term of patent 7 years

(Cl. D54—13)

To all whom it may concern:

Be it known that I, Glenn W. Wolcott, a citizen of the United States of America, residing at Dayton, in the county of Montgomery and State of Ohio, have invented a new, original, and ornamental Design for a Tube Cutter, of which the following is a specification, reference being had to the accompanying drawing, forming a part thereof.

Fig. 1 is a view in perspective of a tube cutter showing my new design with the reamer shown in extended position;

Fig. 2 is a top plan view of the tube cutter with the reamer in extended position; and

Fig. 3 is a side elevational view of the tube cutter with the reamer in retracted position.

I claim:

The ornamental design for a tube cutter, substantially as shown and described.

GLENN W. WOLCOTT.
